UNITED STATES PATENT OFFICE.

WALTER KLINE, OF GREEN TOWNSHIP, SUMMIT COUNTY, OHIO, ASSIGNOR TO F. A. WILCOX, OF AKRON, OHIO.

PLURAL-WALLED CAN.

1,191,319.

Specification of Letters Patent. Patented July 18, 1916.

Application filed August 9, 1915. Serial No. 44,477.

To all whom it may concern:

Be it known that I, WALTER KLINE, a citizen of the United States, residing at Green township, in the county of Summit and 5 State of Ohio, have invented new and useful Improvements in Plural-Walled Cans, of which the following is a specification.

This invention relates to plural-walled containing receptacles, such for instance as 10 cans, wherein the provision of a plurality of spaced walls prevents the conduction or transmission of heat or cold through the walls either from the inside outwardly or from the outside inwardly.

15 The object of the invention is to provide a containing receptacle such as a can, coffee-pot, teapot, bottle, jar, or other article of any form or description with a wall constructed to prevent the transmission or con- 20duction of heat or cold therethrough without the necessity of employing a vacuum as a non-conductor.

The invention further contemplates the production of a containing receptacle of the 25 type heretofore described which may be formed of metal to render the same stronger and more durable and provided with walls which are highly efficient as non-conductors of heat or cold.

30 With the foregoing and other objects in view, the invention consists in the novel construction, combination and arrangement of parts constituting the invention to be hereinafter specifically described and illustrated 35 in the accompanying drawing which forms a part hereof wherein is shown the preferred embodiment of the invention, but it is to be understood that changes, variations and modifications can be resorted to 40 which come within the scope of the matter hereinafter claimed.

The drawing presented is a vertical, central, sectional view of a simple form of containing receptacle or can embodying this 45 present invention.

A receptacle or can embodying this invention is shown in its simplest form in the drawing, and as shown comprises an outer member provided with a lateral wall 1 50 united to or formed integrally with the bottom wall 2 both preferably formed of spun metal such as thin aluminium, but the shape, size and dimensions of the outer member is immaterial to this invention. Positioned within the outer member and spaced

therefrom is an inner member having a lateral wall 3 united with a lower wall 4 or made integral therewith and the wall 3 preferably provided with an outwardly-flaring shoulder 5 from which extends an 60 upwardly-projecting inverted frusto-conically-formed flange 6 having a spaced downwardly-bent flange 7. The transverse diameter of the inner member, formed by the wall 3, is considerably less than the trans- 65 verse diameter of the outer member formed by the wall 1 so as to provide between the two metallic walls an air space 8. The interior diameter of the flange 7 is such as to nicely fit the upper marginal portion of the 70 wall 1 and the two are secured together by some means, such for instance, as brazing or soldering. Positioned between the walls 1 and 3 and spaced from both is a cup-shaped member having a lateral wall 9 and a lower 75 wall 10 preferably formed integrally therewith and the whole preferably formed of sheet asbestos. At the upper marginal portion of the wall 9 is an upwardly-flaring portion 10 arranged to be secured to the 80 outer face of the shoulder 5 by some means such for instance as cement. The asbestos member will conform in contour generally with the outline of the walls 1 and 3 but sufficiently spaced therefrom to be entirely 85 out of contact therewith.

In assembling a receptacle or can such as is shown in the drawings, the asbestos member is slipped over the inner member so that the walls of the two are in spaced relation and the outwardly-flared portion 10 cemented to the shoulder 5, after which the outer member provided with the wall 1 is positioned and the joint between the marginal portion 90 of the wall 1 of the outer member and the 95 downturned flange 7 of the inner member united by any desired means.

It will be noted that the inner face of the 100 upwardly-extending flange 6 is conical and constitutes a frictional seat for a closure member designated generally by the numeral 11 which comprises an inner member formed preferably of sheet metal such, for instance, as aluminium, with an upper wall 12 and a 105 downwardly-turned marginal flange 13 from which projects upwardly a flange 14, the outer face of which is conically fashioned and of proper diameter to snugly and frictionally engage the inner face of the flange 6. Secured over the upper outer portion of the 110

flange 14 is a cap 15 arranged in spaced relation to the walls 12 and 13 and overlapping the flanged portion 14 at the marginal portion thereof and which is secured thereto by brazing or soldering or any other preferred method. Positioned between the walls 12 and 15 and arranged in spaced relation with respect thereto is a wall of non-conducting properties such, for instance, as 10 a layer of asbestos 16 provided at the marginal portion with a downturned flange 17 which is secured in the channel or groove formed between the walls 13 and 14 by any appropriate means, such for instance, as cement or other equal efficient means.

It is pointed out that the entire closure member 11 may be formed so that the walls 12, 13, 14 and 15 may be integral if the latter method proves commercially practical 20 and so long as the wall 12 is separate from the wall 15 and the wall 13 from the wall 14 and both arranged in spaced relation with respect to the non-conducting member 16. By the provision of a can or receptacle such 25 as has just been described the transmission of changes of temperature through the composite walls is substantially entirely prevented and results are obtained equal to the

employment of a vacuum between a double-walled receptacle or jar.

30

I claim:—

A receptacle comprising a cup-shaped inner member of sheet metal provided at the upper end with an outwardly flaring integral flange from which extends upwardly a wall flaring outwardly with an inclination less than the inclination of said flange, said wall terminating at its upper part with an integral downturned portion, a cup-shaped member of non-metallic material larger than the first member arranged around and in spaced relation therewith and provided with an outwardly flaring upper portion adapted to be attached to the outer face of said flange, a cup-shaped metallic member larger than said last member positioned thereabout and in spaced relation therewith, the upper portion thereof secured to and lapping the down-turned upper portion of the first member, and a cover for said receptacle arranged to frictionally engage the inner face of the flaring wall of the first member substantially as described.

35

In testimony whereof I have hereunto set my hand.

WALTER KLINE.
